US00D570449S

(12) **United States Design Patent** (10) Patent No.: **US D570,449 S**
Lee (45) Date of Patent: **** Jun. 3, 2008**

(54) **SINK FIXTURE**

(75) Inventor: **William A. Lee**, Wheaton, IL (US)

6,067,670 A 5/2000 Eddy et al.
6,360,770 B1 3/2002 Buchner et al.
6,775,866 B1 8/2004 Martir et al.
6,918,400 B2 7/2005 Buchner et al.

(73) Assignee: **Marcoll International Corp.**, Omaha, NE (US)

* cited by examiner

(**) Term: **14 Years**

Primary Examiner—Robert M. Spear

Assistant Examiner—Ania K Dworzecka

(21) Appl. No.: **29/269,446**

(74) Attorney, Agent, or Firm—Patterson, Thuente, Skaar & Christensen, P.A.

(22) Filed: **Nov. 30, 2006**

(57) **CLAIM**

(51) **LOC (8) Cl.** **23-01**

I claim the ornamental design for sink fixture, as shown and described.

(52) **U.S. Cl.** **D23/238**

DESCRIPTION

(58) **Field of Classification Search** D8/305,

FIG. 1 is a front, right perspective view of a sink fixture showing my new design;

D8/310, 321, 322; 4/678, 677, 675; D23/238,

FIG. 2 is a top plan view of the sink fixture in FIG. 1;
FIG. 3 is a left side elevation view of the sink fixture in FIG. 1; and,

D23/242, 243, 244, 245, 249, 250, 251

FIG. 4 is a front elevation view of the sink fixture of FIG. 1.

See application file for complete search history.

In the drawings, the broken lines depict environmental subject matter only and form no part of the claimed design.
